HYPODERMIC SYRINGE UNIT

George K. Burke, Bethlehem, Pa., assignor to Burron Medical Products, Inc., Bethlehem, Pa., a corporation of Pennsylvania

Filed Sept. 3, 1958, Ser. No. 52,492

Term of patent 14 years

(Cl. D83—12)

FIG.1

FIG.2

FIG.3

FIG.4

FIG.5

FIG.6

Fig. 1 is a perspective view of one end of a hypodermic syringe showing my new design, the terminal end of the plunger being shaded to show contrasting color;

Fig. 2 is a perspective view of the other end thereof with the needle and needle cap omitted for convenience of illustration;

Fig. 3 is a fragmentary side elevational view showing the syringe barrel thereof;

Fig. 4 is a fragmentary side elevational view showing the syringe plunger thereof;

Fig. 5 is a fragmentary perspective view showing the needle cap thereof; and

Fig. 6 is a fragmentary vertical cross-sectional view taken on line 6—6 of Fig. 2.

The dominant feature of the invention resides in the full line portions of the drawing.

I claim:

The ornamental design for a hypodermic syringe unit, as shown and described.
